UNITED STATES PATENT OFFICE.

WILL G. SHEEMAN, OF CHICAGO, ILLINOIS.

OIL BURNER.

Application filed January 22, 1925. Serial No. 4,069.

To all whom it may concern:

Be it known that I, WILL G. SHEEMAN, a citizen of the United States, residing at Chicago, in the county of Cook and State 5 of Illinois, have invented certain new and useful Improvements in an Oil Burner, of which the following is a specification.

This invention relates to improvements in oil burners and has for its principal object 10 to provide one that generates and superheats its own steam.

Another important object of the invention is to provide an oil burner of the above mentioned character wherein the water trap 15 is provided for automatically regulating the water level in the boiling chamber thus insuring the efficient operation of the steam generating and superheating means.

A still further object of the invention is 20 to provide an oil burner of the above mentioned character, which is simple in construction, inexpensive, strong and durable and furthermore adapted for the purposes for which it is designated.

25 Other objects and advantages of this invention will become apparent during the course of the following description.

In the accompanying drawing forming a 30 part of this specification and in which like numerals designate like parts throughout the same:

The figure represents a vertical sectional view of the burner embodying my invention.

In the drawing wherein for the purpose 35 of illustration is shown the preferred embodiment of my invention, the numeral 1 designates the supporting base, the same being provided with a central threaded opening 2. A circular burner head 3 extends upwardly from the base 1 around the opening 2. Threaded at its lower end in the threaded 40 opening 2 of the base 1 and extending through the burner head 3 is the body member designated generally by the numeral 4.

45 The body member 4 is provided with a vertically extending water inlet passage 5, a supply pipe 6 being threaded into the lower end of the body member and communicating with the passage 5. An atomizing 50 or mixing chamber 7 is arranged centrally within the body member and communication between the mixing chamber and the burner head 3 is provided through the medium of the fuel passage 8. The body member 4 is also provided with an oil inlet 55 passage 9 which communicates with the at-

omizing or mixing chamber 7. An oil supply pipe 10 is threaded into communication with the oil passage 9 in the lower portion of the body member. A water outlet passage 11 is provided in the lower portion of the body member 4 and a discharge pipe 12 is associated with the outlet passage 11. The purpose of the water passage will hereinafter be more fully described.

Threaded on the body member 4 at a point adjacent the top of the burner head 3 is the water boiling chamber 13. Arranged in superposed relation above the boiling chamber 13 and communicating therewith are a plurality of steam chambers 14. Each of the steam chambers is provided with a central opening 15 and extending through the openings 15 is the superheated steam conduit 16, the same being formed as an integral part of the body member 4 at the upper portion thereof. The steam chambers 14 are preferably in the form of hollow circular disks. The upper portion of the body member 4 is disposed within the boiling chamber 13 and formed in the upper portion of the body member is a water trap designated generally by the numeral 17. An inlet 18 is associated with the water trap 17 and provides a means whereby the water level in the boiling chamber 13 will be regulated. A superheated steam passage 19 extends vertically in the upper portion of the body member 4 communicating with the steam conduit 16 at its upper end and having the lower end thereof communicating with the atomizing or mixing chamber 7. The lower end of the superheated passage 19 is furthermore disposed directly opposite the oil inlet passage 9 as clearly illustrated in the drawing.

Baffle plates such as are shown at 20 are arranged on the steam conduit 16 at a point adjacent the openings 15 provided in the steam chambers 14. The burner head 3 has its inner periphery spaced from the body member 4 to provide an annular burner outlet 21.

In operation, the burner head 3 is initially primed, and water is admitted to the boiling chamber 13 through the pipe 6 and the water passage 5. The flames from the burner will heat the boiling chamber 13 causing steam to be generated. The steam will pass upwardly through the steam chambers which provide a means for superheating the steam, the steam passing through the open-

ings 15 and around the baffles 20. The steam chambers 14 are also exposed to heat radiation and thereby the steam upon passing upwardly through the steam chambers 5 will be properly superheated. The water condensation will return to the boiler chamber 13 and the trap 17 will take care of an overflow in the chamber 13 so that the level of the water will be regulated automatically. 10 The superheated steam will enter the top of the steam conduit 16 and pass downwardly through the passage 19 in the body member 4 where it comes in contact with the oil being admitted to the oil inlet passage 9 through the supply pipe 10. The superheated means and the oil will become atomized or mixed in the chambers 7 and the mixture will be discharged into the burner head 3 through the passage 8. The 15 combustible gas produced will be a gas which will burn with intense flame at the burner outlet 21. The water which may overflow will pass from the trap 17 into communication with the water outlet passage 11 and will be discharged through the pipe 12.

It will thus be seen from the foregoing description, that an oil burner has been provided which will generate and superheat its 20 own steam, the device being at all times positive and efficient in its operation. The simplicity in which my device is constructed furthermore enables the same to be readily and easily assembled or disassembled.

35 While I have shown the preferred embodiment of my invention, it is to be understood that various changes in the size, shape and arrangement of parts may be resorted to without departing from the spirit of 40 the invention and the scope of the appended claims.

Having thus described the invention, what I claim is:—

1. An oil burner of the class described 45 comprising a supporting base having a centrally threaded opening, a burner head on said base around said opening, a body member threaded at its lower end into said threaded opening and extending through 50 the burner head, said body member provided

with an oil inlet, and a mixing chamber communicating with the oil inlet, means enclosing the body member for generating and superheating steam, said body member being provided with means for admitting the superheated steam to the mixing chamber for contact with the oil, said body member being further provided with a fuel passage communicating the mixing chamber with the burner head. 55

2. An oil burner of the class described comprising a body member provided with an oil inlet, and a mixing chamber in communication therewith, a burner head associated with the body member and having communication with the mixing chamber, a water boiling chamber associated with the body member, said body member having means provided therein for admitting water to said chamber, communicating superheating steam chambers arranged above the boiling chamber and communicating therewith, a superheated steam delivery conduit extending through said steam chambers communicating with said mixing 70 chamber, and baffles on said conduit adjacent the inlet of each steam chamber.

3. An oil burner of the class described comprising a body member provided with an oil inlet, and a mixing chamber in communication therewith, a burner head associated with the body member, and having communication with the mixing chamber, a water boiling chamber associated with the body member, said body member having means provided therein for admitting water to said chamber, superimposed super heating steam chambers arranged above the boiling chamber having communication with the latter and further communicating with each other, a superheated steam delivery conduit extending upwardly through the superimposed steam chamber communicating at its lower end with the mixing chamber, and baffles on said conduit adjacent the inlet of each of the superimposed steam chambers. 85 90 95

In testimony whereof I affix my signature.

WILL G. SHEEMAN.
